FIGURE 3

FIGURE 4

A detailed line drawing of a long, thin cylindrical object, likely a tube or a rod. At the left end, there is a flared section with several small rectangular cutouts and a central slot. The numbers 7, 8, 3, 2, 6, 5, 9, and 24 are labeled on this flared section. The main body of the cylinder is labeled with the number 9. At the right end, there is a flared section with a central slot, and the number 34 is labeled on both the main body and this flared section.

UNITED STATES PATENT OFFICE.

MORRIS V. HUBBARD, OF SAN JOSE, CALIFORNIA.

STRETCHER.

1,286,328.

Specification of Letters Patent.

Patented Dec. 3, 1918.

Application filed May 27, 1918. Serial No. 236,836.

To all whom it may concern:

Be it known that I, MORRIS V. HUBBARD, a citizen of the United States, and resident of San Jose, in the county of Santa Clara and State of California, have invented certain new and useful Improvements in Stretchers, of which the following is a specification.

One object of my invention is to provide a device of the character indicated that can be quickly and easily separated on a median line so that a patient may be deposited upon a bed or operating table with a minimum amount of disturbance. Other objects of my invention are to provide a device of the character indicated, 1st, that is provided with a resiliently mounted separable canvas member; 2nd, that can be quickly and easily taken apart and reassembled; 3rd, that is provided with collapsible handles; 4th, that can be folded up into a compact bundle; 5th, that is economical to manufacture, substantial and practical.

With these and other objects in view my invention consists of the novel and useful provision, formation, construction, combination and relative arrangement of parts, members and features, all as hereinafter described, shown in the drawings and finally pointed out in the claims.

50 In the drawings:—

Figure 1 is a plan view of my improved stretcher. Fig. 2 is a side elevation of the device as shown in Fig. 1. Fig. 3 is an enlarged longitudinal sectional view through the central coupling member, parts broken away. Fig. 4 is an enlarged cross sectional view on line 4—4 of Fig. 1. Fig. 5 is a plan view of one set of spacing members in an operative position and adjacent portions 40 of the stretcher proper. Fig. 6 is an inner side elevation of one side member, part broken away. Fig. 7 is a detail illustration of the lock for the spacing device.

Similar characters of reference refer to 45 similar parts throughout the several views. In the following description one half of the device is described in detail and the corresponding parts in the other half are indicated by similar numerals followed by the 50 letter "a".

Referring now more particularly to the drawings, one half of the device consists of a side pole 1 having plates 2 positioned upon either end, each plate 2 having a shoulder 55 3 formed on each side thereof, and an orifice 4 provided near its inner edge. Adjacent

each plate 2, and on either side of pole 1, are links 5 pivotally mounted on bolt 6 passing through pole 1. Each pair of links 5 has a handle 7 pivotally connected thereto by pivots 8, the handle 7, links 5 and plate 2 being so proportioned and so positioned with relation to each other that when the handle 7 is turned downwardly into the position B links 5 will engage shoulders 3 on plate 2 and thereby be held from further rotation while handle 7 may be swung around on pivots 8 into the position C. A portion of the under side of pole 1 is removed as at 9 to form a recess or pocket for handle 7 when it is thus revolved into position C.

Hooked into orifices 4 and into eyes 10 spaced along the inner side of pole 1, are a number of springs 11. At 12 is indicated a canvas sheet having a rod 13 positioned adjacent its outer and longer edge and around which the several springs 11 are hooked. Along the inner edge of sheet 12 are spaced a number of canvas loops 14, the same alternating with similar loops 14^a spaced along the inner edge of sheet 12^a. At 15 is indicated a coupling member positioned in loop 16 attached to sheet 12, and threaded as at 17 and 18 respectively to receive the threaded ends of rods 19 and 20. The rods 19 and 20 are provided with suitable handles as 21 and 22 and when passed through the alternating loops 14 and 14^a and into coupling 15 securely fasten the two halves of the device together. Additional handles 23 are secured to the outer side of pole 1.

The spacing devices, one at each end of the stretcher, are identical in construction and therefore but one is described. Pivoted to pole 1 near handle 7 is a bar 24 having a notch 25 formed in its inner edge and at a point that is midway between poles 1 and 1^a when the spacing device is in an operative position. The free end of bar 24 is bent downwardly and inwardly to form a hook 26. On the upper surface of bar 24 is placed a spring 27 carrying a pin 28 which operates freely through orifice 29 in bar 24. At 30 is shown a second bar pivotally mounted on pole 1^a near handle 7^a and carrying a pin 31 on its upper side adapted to engage notch 25 in bar 24 as hereinafter described, the free end of bar 30 being bent upwardly and inwardly to form a hook 32. An orifice 33 is formed in bar 30 to receive

pin 28 when the device is in an operative position. When the stretcher is not in use each member 24 and 30 is folded back into a recess formed in the inner side of its respective pole, one of these recesses being shown clearly at 34.

Supposing now that an emergency call is received and the stretcher is required. It is taken down and the handles 7 and 7^a are 10 swung into position, the canvas straightened out and bars 24 and 30 swung out into such a position as indicated in dotted lines at 24^a and 30^a in Fig. 5. Shoving the two bars forwardly forces pin 31 into notch 25, causes 15 hook 32 to engage bar 24 and hook 26 to engage bar 30, and pin 28 to engage orifice 33 thereby securely locking the parts in the position shown. The patient is now placed upon the stretcher in the usual manner. The 20 stretcher with the patient upon it may now be placed upon a table, or by folding handles 7 and 7^a inwardly into the position C it may be placed directly upon a bed of standard length.

25 The stretcher may now be removed with a minimum amount of discomfort to the patient by simply unscrewing and removing rods 19 and 20, thus permitting the two halves of the stretcher to be withdrawn 30 without removing the patient. By realining loops 14 and 14^a and replacing rods 19 and 20 and screwing the same into coupling 15 and relocking the spacing members, the stretcher is again rendered ready for use, 35 or the spacing devices may be folded back into their respective recesses and the whole device rolled up until again needed. If the canvas 12 becomes soiled it may be readily removed for washing by removing rods 19 and 20 and 13 and unhooking springs 11. The extreme ends of canvas 12 are supported by buttoned straps as at 35.

Additional comfort is secured to the patient by the use of springs 11 because these 45 springs absorb a great deal of the vibration incident to moving, especially if the patient is to be carried some distance as in an ambulance.

While I have herein shown and described 50 one specific form of my invention, it is understood that changes in form and construction may be made within the scope of the appended claims.

I claim:—

55 1. A stretcher comprising a pair of side rails, a pair of elongated flexible supporting members resiliently attached to said rails at their outer edges, means for detachably connecting said flexible members at their 60 inner edges, collapsible means for locking said side rails in spaced relation to each other against the tension of said connected and resiliently mounted flexible members, and foldable handles operatively mounted 65 upon the ends of said side rails.

2. A stretcher comprising a pair of side rails, a pair of elongated flexible supporting members resiliently attached to said rails at their outer edges, means for detachably connecting said flexible members at their 70 inner edges, and separable interlocking means pivotally mounted on said rails for spacing said rails and holding said members under tension, said rails having recesses formed therein to receive said interlocking 75 means when not in an operative position.

3. A stretcher comprising a pair of side rails, an elongated flexible supporting member attached to each rail at its outer edge, and means for detachably connecting the 80 said flexible supporting members at their inner edges, said means comprising a coupling tapped at each end to receive threaded rods and secured to one supporting member adjacent its inner edge and midway the 85 length of said edge, a plurality of loops spaced along said edge in alignment with said coupling, a plurality of loops spaced along the inner edge of the other supporting member and adapted to alternate with the 90 first mentioned loops, and rods having threaded ends adapted to engage both sets of loops and said coupling and maintain the same in alignment, and each of said rods having a handle attached to its outer end. 95

4. A stretcher comprising a pair of side rails, an elongated flexible supporting member attached to each rail at its outer edge, and means for detachably connecting the 100 said flexible supporting members at their inner edges, said means comprising a coupling secured to one supporting member adjacent its inner edge and midway the length of said edge, a plurality of loops spaced along said edge in alignment with said coupling, a plurality of loops spaced along the inner edge of the other supporting member and adapted to alternate with the first mentioned loops, and rods adapted to engage both sets of loops and said coupling and 110 maintain the same in alignment.

5. A stretcher comprising a pair of side rails, an elongated flexible supporting member attached to each rail at its outer edge, and means for detachably connecting the 115 said flexible supporting members at their inner edges, said means comprising a coupling secured to one supporting member adjacent its inner edge and midway the length of said edge, a plurality of loops 120 spaced along said edge in alignment with said coupling, a plurality of loops spaced along the inner edge of the other supporting member and adapted to alternate with the first mentioned loops, and rods adapted 125 to engage both sets of loops and said coupling and maintain the same in alignment and independent means for detachably connecting the extreme ends of the inner edges of said supporting members. 130

6. In a stretcher, separable means for locking the side rails in spaced relation to each other, said means comprising a bar pivotally mounted on each rail, each bar having an inwardly directed hook formed on the end thereof adapted to engage the outer edge of the other bar when the device is in an operative position, one bar having a notch formed in its inner edge and directed 10 toward its pivoted end and the other bar having a pin positioned on its under surface adapted to engage said notch when the device is forced into an operative position, and means for locking said pin in engagement 15 with said notch and said hooks in engagement with their respective edges of said bars.
7. A stretcher comprising a pair of side rails, a separable, elongated flexible supporting member, and means for attaching said supporting member to said side rails, said means comprising a rod removably positioned at each of the two longer edges of said supporting member and a plurality of 20 resilient members removably attached to each of said rails and the adjacent rod.
8. A stretcher comprising a pair of side rails, an elongated flexible supporting member, and means for removably attaching said supporting member to said side rails, said means comprising a loop formed in each of the two longer edges of said supporting member, a rod removably inserted in each 25 loop, a perforated plate secured to each end 30 of each side rail, a plurality of eyes arranged along the inner edge of each side rail, and a resilient member connected to each of said perforated plates and said eyes
- and removably connected to the adjacent rod. 40
9. A stretcher comprising a pair of side rails, a separable, elongated, flexible supporting member, and means for attaching said supporting member to said side rails, said means comprising a rod removably positioned at each of the two longer edges of 45 said supporting member and a plurality of resilient members attached to each of said rails and the adjacent rod.
10. The combination with the side rails 50 of a stretcher of a folding handle and stop device, comprising a shouldered plate secured to the upper surface of the end of said rail, a link pivotally mounted on each side of said rail and adapted to engage 55 said shouldered plate when positioned at a predetermined angle to said rail, and a handle pivotally connected to both of said links, said side rails being provided with recesses on their under sides to receive said 60 handles when folded.
11. A stretcher comprising a pair of side rails having folding handles mounted on the ends thereof, and recesses to receive said handles when folded, a separable, 65 elongated, flexible supporting member attached thereto, and separable, interlocking means for spacing said rails and holding said supporting member under tension, said rails having recesses formed therein to receive 70 said interlocking means when not in an operative position.

In testimony whereof I have hereunto affixed my signature this 18th day of May, 1918.

MORRIS V. HUBBARD.
